(57) **CLAIM**

I claim the ornamental design for a detachable bottle top container, as shown and described.

DESCRIPTION

FIG. 1 is a perspective view of a detachable bottle top container showing my new design;

FIG. 2 is a top view of the detachable bottle top container thereof;

FIG. 3 is a bottom view of the detachable bottle top container thereof;

FIG. 4 is a front view of the detachable bottle top container showing features thereof;

FIG. 5 is a rear perspective view of the detachable bottle top container in same position thereof;

FIG. 6 is a right side view of the detachable bottle top container in same position thereof; and,

FIG. 7 is a left side view of the detachable bottle top container in same position thereof.

The broken lines shown on the drawings depict environment and form no part of the claimed design.
